(57) CLAIM

We claim the ornamental design for a side region of a sports equipment bag, as shown and described.

DESCRIPTION

FIG. 1 is an upper, side perspective view of a sports equipment bag; and,

FIG. 2 is a first side view of the sports equipment bag of FIG. 1.

The broken lines immediately adjacent the shaded areas represent the bounds of the claim and all other broken lines are for illustrative purposes only. None of the broken lines form part of the claimed design.
